UNITED STATES PATENT OFFICE.

CHARLES HENRY NAYLOR, OF RUGBY, ENGLAND, ASSIGNOR TO GENERAL ELECTRIC COMPANY, A CORPORATION OF NEW YORK.

ELASTIC-FLUID TURBINE.

1,110,508.

Specification of Letters Patent. Patented Sept. 15, 1914.

Application filed June 26, 1913. Serial No. 775,856.

To all whom it may concern:

Be it known that I, CHARLES HENRY NAYLOR, a subject of the King of Great Britain, residing at Rugby, in the county 5 of Warwickshire, England, electrical engineer, have invented certain new and useful Improvements in and Relating to Elastic-Fluid Turbines, of which the following is a specification.

10 This invention relates to elastic fluid turbines and more particularly to turbines which are utilized to drive a rotary condenser operating in conjunction with a prime mover such as a reciprocating engine 15 capable of working efficiently with a vacuum of about 25 or 26 inches. Such turbines are driven by the exhaust steam passing from the engine to the condenser. In some cases however the amount of steam supplied 20 is greater than can pass through the turbine and in other cases there may be an insufficient quantity or the pressure of the exhaust may be too low to drive the turbine.

The object of my invention is to construct 25 an improved turbine of this type.

For a consideration of what I believe to be novel and my invention, attention is directed to the accompanying description and the claims appended thereto.

30 Figure 1 is a vertical section through a turbine illustrating one of the embodiments of my invention, and Fig. 2 is a diagrammatic view showing a reciprocating engine and turbine installation.

35 In carrying my invention into effect according to the modification illustrated in the accompanying drawing, I provide a mixed pressure turbine the rotor 1 of which may be mounted on the shaft 2 carrying 40 the impeller 3 of the rotary condenser. The specific structure of the condenser forms no part of the present invention and may be of any suitable construction. The inlet nozzles 4 for the low pressure steam extend

45 practically completely around the periphery with the exception of a small space within which are inclosed one or two nozzles 5 adapted to receive steam from a high pressure source of supply. With the 50 exception of these one or two nozzles the remainder of the nozzles are situated in an annular space 6 into which the exhaust from the prime mover is discharged through the conduit 7. The rotor of the turbine consists of a spider 8 having an annular outer

rim 9 to which the moving blades are secured. Mounted in the space inclosing the high pressure inlet nozzles is a high pressure steam conduit controlled by a valve 11. This valve is held on its seat by means of 60 a spring 12 and opened by means of a spindle 13 controlled by the governor 14 and acting against the spring. Mounted on the spindle which operates the high pressure valve is a by-pass valve 15 which controls 65 an aperture through which the low pressure steam may pass to an annular chamber 16 one side of which is bounded by the rotor of the turbine so that steam entering the chamber through the valve 15 may pass 70 through between the arms of the rotor and so to the condenser without passing through the turbine blade. The by-pass valve is operated by the speed governor 14 in such a manner that as the speed of the turbine 75 rises above a predetermined point the valve opens and allows some of the low pressure steam to pass to the condenser without doing work on the turbine blades. If, on the other hand, the supply of low pressure 80 steam is insufficient to keep the speed up to the required point the spindle 13 of the by-pass valve is moved so as to cause the high pressure valve 12 to open and admit 85 live steam to the few nozzles 5 controlled by said valve. The movement of the spindle to open the high pressure valve may cause the by-pass valve 15 to close entirely or may cause it to pass through its closed position and open again in the opposite direction so that very little of the low pressure steam need pass through the turbine blades while the turbine is being supplied with high pressure steam. In Fig. 2 the turbo-condenser is illustrated as being connected 90 to the exhaust conduit 31 of a high pressure reciprocating engine 30.

I do not wish to limit myself to any particular construction of valves or governing mechanism, as it will be obvious that the 100 construction may be varied considerably without departing from the spirit of my invention.

What I claim as new and desire to secure by Letters Patent of the United States is:— 105

1. In a turbine, the combination of a casing, a supply conduit, a bladed rotor in the casing having a fluid conveying passage that is independent of and shunts the blades, devices for discharging fluid against the 110

blades, and a valve controlled conduit for shunting the motive fluid around said blades and devices and into the passage in the rotor.

5. 2. In a turbine, the combination of a casing, inlet and discharge conduits therefor, a bladed rotor in the casing having a fluid conveying passage located between its shaft and blades, devices for discharging low pressure motive fluid against the blades, a valve controlled conduit for shunting motive fluid around said blades and devices and into the passage of the rotor, and means for admitting motive fluid to the rotor from a separate source when the first named supply is deficient.
3. The combination with a high pressure engine and a casing containing a rotary condenser therefor, of a bladed rotor therein to 20 which the low pressure steam is freely admitted on its way to the condenser, a by-pass in the casing around the rotor for permitting low pressure steam to pass directly to the condenser without acting on the rotor, 25 valve means controlling it, an inlet for sup-

plying high pressure steam to the turbine rotor, controlling valve means therefor, and a governor controlling both the valve means aforesaid so that when the supply of low pressure steam becomes excessive it is bypassed to the condenser and so that when said supply is insufficient high pressure steam is admitted.

4. The combination with a high pressure engine and a casing containing a rotary condenser therefor, of a turbine rotor mounted in the casing for driving the condenser, means for directing the exhaust from the engine to the rotor, a by-pass which shunts the directing means, a valve controlling said by-pass, and means for opening said valve to shunt any excess of exhaust steam above that required to drive the turbine rotor, directly to the condenser.

In witness whereof, I have hereunto set 45 my hand this tenth day of June 1913.

CHARLES HENRY NAYLOR.
